UNITED STATES PATENT OFFICE.

EDWARD B. HINE, OF LONGMEADOW, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

REGISTER.

Application filed April 30, 1921. Serial No. 465,789.

To all whom it may concern:

Be it known that I, EDWARD B. HINE, a citizen of the United States, residing at Longmeadow, in the county of Hampden 5 and State of Massachusetts, have invented new and useful Improvements in Registers, of which the following is a specification.

This invention relates to improvements in registers of the type which are intermittent- 10 ly actuated,—usually from a machine, to give cumulative indications of the extent of motion of some part of the machine.

The invention, according to most of its features, is capable of a variety of uses and is 15 thus largely independent of the particular use to which it is put.

The invention, however, finds one advan- 20 tageous use in connection with the well-known measuring and dispensing pumps, which are generally used in connection with the sale of gasoline and like oils. For such use, it is highly desirable to prevent fraudulent operation of the register, which is the means for apprising the customer of the 25 quantities displaced from the pump. If such means can, without great difficulty, be fraudulently manipulated, dishonest operators will take advantage of this fact to mislead and cheat the customer.

One object of the invention is to provide 30 in a register indicator-operating mechanism with an actuator adapted to be moved intermittently to cause the indicator to progress and give the desired cumulative indications, such mechanism arranged to prevent such 35 progress by any other means than said actuator and, while permitting reverse movement of the indicator to zero position, prevents such movement beyond such position.

Another object of the invention is to provide 40 a reciprocable actuating means for periodically engaging the actuator on each stroke and capable of moving it on only one, said means including a part which can yield 45 readily when it engages the actuator on its inoperative stroke and can also yield after it has engaged and moved the actuator on its operative stroke but less readily than on the other stroke.

Another object of the invention is to provide, 50 as indicator-operating mechanism, an escapement wheel and an associated oscillating operating lever, the teeth of said wheel for the most part permitting retrograde

movement relative to said lever, but there 55 being at least one tooth so formed as to prevent such movement, whereby the indicator cannot be moved backwards beyond a pre-determined point, such, for example, as the zero point of the register.

Another object of the invention is to encase 60 the operating mechanism in such a manner that it cannot be taken apart when mounted on the machine from which it is operated, and to encase such machine, or at 65 least the above-described actuator and its actuating means, leaving only the indicator of the register and some controlling device for the machine accessible from outside the casing.

The invention, in an embodiment at present preferred, is disclosed for illustrative purposes in the accompanying drawings, in which,—

Fig. 1 is a cross-sectional view of a register, embodying the invention, illustrative also of the mounting of the register on the machine by which it is operated;

Fig. 2 is a fragmentary elevational view of the register-operating mechanism, the enclosing casing of which has been largely broken away;

Fig. 3 is a sectional elevational view, taken on the line 3—3 of Fig. 1 and illustrative of the preferred construction of the actuator; and

Fig. 4 is a small-scale elevational view showing the encased machine with the register mounted thereon.

Referring to these drawings, the operating mechanism is completely enclosed in a suitable casing which, as illustrated, consists of front and back members 5 and 6, respectively, one of which, as 5, has a circular rim 7 to suitably space the members and complete the enclosure. These members are suitably secured together, as by screws 8, which are preferably applied from the back of the register for the purpose of rendering them inaccessible for removal after the back 95 plate has been mounted, as shown in Fig. 1, on the machine by which it is to be driven.

The outer face of the front member 5 carries a dial suitably graduated in the desired units, as indicated at 9 in Fig. 4. For the 100 sake of illustration, these units may be considered as gallons, inasmuch as the machine illustrated in connection with the register is

2
a measuring and dispensing pump. The indicator, as illustrated, consists of a pointer 10 fixed to the outer end of a shaft 11 mounted to turn in suitable bearings in members 5 and 6.

The operating mechanism of the register comprises an escapement wheel 12 and a suitable oscillating operating lever 13. Wheel 12 is suitably fixed to shaft 11 and closely fits between hubs on members 5 and 6, thereby preventing axial movement of the shaft. The operating lever is fixed intermediate its ends to another, and parallel, shaft 15 which is mounted in a hub 16 projecting rearwardly from back-plate 6. The free ends of lever 13 are arranged alternately to engage the teeth of wheel 12 in any suitable manner, as by the pins 16' illustrated. These pins, arranged one near each end of lever 13, project laterally therefrom into the plane of the wheel, the lever itself, as shown in Fig. 1, being disposed in back of the wheel. The relation of lever 13 to wheel 12 is such that one pin 16' enters a tooth space 17 just before the other pin 16' leaves a corresponding tooth space, so that at no time, even for an instant, does the lever release the wheel for forward movement by any other means than the lever itself, although retrograde movement of the wheel, as far as the zero point of dial 5 can be effected manually, as by turning the handle 18 which, as shown in Fig. 2, is fixed to indicator 10.

For the purpose of permitting retrograde movement of wheel 12 independently of lever 13, the teeth of the wheel are, for the most part, formed as ordinary ratchet teeth. Such teeth are indicated at 19 and have one radial face 20, the upper end of which is connected to the lower end of the corresponding face of the adjacent tooth by an inclined, or cam, face 21. At least one of the teeth, as 22, has its cam face modified as shown in Fig. 2, to afford a shoulder 23, which is so located as to prevent retrograde movement of the wheel beyond the point described. When the wheel is turned backwards to such point, the upper pin 16' will by engagement with shoulder 23 prevent further movement in this direction, such shoulder being disposed at right-angles, or substantially so, to the line connecting the centers of shaft 15 and pin 16', when lever 15 is in the position illustrated by full lines in Fig. 2.

Preferably, the tooth immediately preceding tooth 22—that tooth, as 24, which on retrograde movement of wheel 12 would be engaged by the upper pin 16' just prior to its drop into the space between teeth 22 and 24—has its point slightly modified as by rounding it as indicated at 25. This is desirable, although not necessarily essential in all cases, to insure that, on rapid retrograde movement of wheel 12, the pin 16' will

strike low enough on the back face of tooth 22 to engage and be arrested by the shoulder 23. On slow return movement of wheel 12, the rounded portion 25 would not be essential.

70

The means for actuating lever 13 will now be described. Actuation of this lever in one direction is effected by a spring 26, or other equivalent means, which tends to hold lever 13 in the illustrated position, viz., with the upper pin 16' located in the bottom of a tooth space 17. When so located, forward movement of wheel 12 is prevented by the abutment of pin 16' with the radial, or substantially radial, face of the teeth 17, 22 or 24. For moving lever 13 in the opposite direction, an actuator, in the shape of a projection, such as 27, is provided which is fixed to the outer end of shaft 15. This projection 27 is arranged to be intermittently engaged and moved by a projection, such as 28, on any moving part, such as the reciprocating bar 29. On such movement, the lower pin 16' engages the cam face of a tooth 19 and moves it forwardly until pin 16' lodges in the bottom of the space 17. This moves wheel 12 forwardly by a distance equal to half that by which the teeth are spaced. Subsequently, the projections 27 and 28 are disengaged, whereupon the upper pin 16' will engage on the cam face of a tooth 19 and move it the remaining distance. Thus, one cycle of movement of lever 13 moves wheel 12 by a step corresponding to that between successive teeth 19 and thus moves indicator 10 one unit over the dial 5.

190

The disengagement of the projections 27 and 28 may, according to the features outlined in the preceding description, be made to occur in any suitable manner. According to one feature of the invention, however, this disengagement is made to occur by the projection 28 tripping over the projection 27 after the former has moved the latter the required distance. That is, the bar 29 continues to move in the same direction and carries one or more projections 28 successively past projection 27, thereby actuating the indicator periodically in its stroke. This arrangement is desirable for adapting the register to a special use in connection with a measuring and dispensing pump.

105

A preferred construction of the projection, or actuator 27, for facilitating operation in a manner similar to that just alluded to, is shown in Fig. 3. The projection 27 consists of the free end of a piece of flat spring material 30, which is fastened at its other end by inserting it in a slot 31 formed in the ends of shaft 15 and a collar 32 fixed to the latter. From its fixed end, the member 30 is bent upwardly over collar 32 and then extends substantially tangential to the latter and substantially par-

120

125

130

allel to the part 27, to a distance from the collar where it is bent backwardly upon itself to form the portion 27 which rests against the collar 32.

5 The practical result of this construction is to provide a projection 27 which is yieldable when engaged on either side by another projection, such as 28, but much less readily yieldable in one direction than the other. Thus, on the upstroke of member 28, it will engage projection 27, but the latter tends to bend from its point of contact with collar 32 and offers considerable resistance to the projection 28. It is intended that, under such circumstances, the projection will not yield to any substantial degree until the lever 13 has been moved, but as soon as the latter is arrested, it can yield, if necessary, to permit projection 28 to pass it. On a return stroke of the latter, the projection 27 yields readily to permit projection 28 to pass it, because it moves away from the collar and can open up and deflect the hitherto parallel portions of member 30 into diverging relation.

It will be seen from the foregoing description that indicator 10 cannot be moved forwardly except by means of the actuator. To further discourage improper actuation 30 of the register, the actuator itself is enclosed with the machine by which it is operated, leaving only the dial 5 and indicator 10 exposed together with a controlling member, as the handle *a* (Fig. 4), for the machine. Such machine, as illustrated, is a measuring and dispensing pump which may be of the general type disclosed in U. S. Letters Patent No. 1,302,014, granted April 29, 1919, on an invention of John B. Davis, 35 to which reference is made for a full disclosure of the pump, its actuating mechanism and enclosing casings. For the present purposes, it will suffice to state that the pump is enclosed by a casing *b* upon which is superimposed a casing *c*, to which the register is attached, and upon the casing *c*, another casing *d*. The casings *c* and *d* house reciprocating members for operating the pump piston, of which members bar 29 40 is an exemplification. Doors *e* are provided to permit access, by authorized persons, to the parts enclosed within casing *c*. Into this casing the shaft 15 is inserted through an opening *f*, and the register is secured to this casing by screws 35 applied from within the casing through one of the doors *e*. With these doors closed and locked, the op-

erator has accessible only the pump-operating handle *a* and the indicating and resetting portions of the register. Thus, the register is rendered proof against fraudulent actuation.

The invention has been disclosed herein, in an embodiment at present preferred, for illustrative purposes, but the scope of the invention is defined by the appended claims rather than by the foregoing description.

What I claim is—

1. In a register having relatively movable indicating elements, an escapement 70 mechanism for actuating one of said elements, including a wheel and an oscillatable lever having two arms alternately engageable with the wheel, said wheel having teeth, most of which are formed so as to permit 75 the wheel to be turned in one direction, but at least one of which is formed to engage with said lever to prevent turning of the wheel in said direction beyond a predetermined point and all of which teeth are 80 formed to prevent the wheel from being turned in the other direction except by oscillation of said lever.

2. In a register, having relatively movable indicating elements, an escapement 80 mechanism for actuating one of said elements, including a wheel and an oscillatable lever having two arms alternately engageable with the wheel, said wheel having teeth all of which have one face so formed 85 as to prevent movement of the wheel in one direction except by said lever and most of which have the other face so formed as to permit the wheel to be turned in an opposite direction, at least one of said teeth 90 having its other face so formed as to engage said lever to prevent further movement in the last-named direction.

3. In a register, having relatively movable indicating elements, an escapement 100 mechanism for actuating one of said elements, including a ratchet-wheel and an oscillatable lever having two arms alternately engageable with the wheel, to rotate it in one direction, the inclined face of one of the 105 teeth of said wheel being cut away to provide a substantially radial shoulder adapted to cooperate with one of said arms to limit the rotation in the opposite direction of said wheel.

In testimony whereof I have affixed my signature.

EDWARD B. HINE.
